Henry Soth;

By Charles Turner Brown,
Atty.

UNITED STATES PATENT OFFICE.

HENRY SOTH, OF ALBERT LEA, MINNESOTA, ASSIGNOR TO ALBERT LEA SPRAYER CO., OF ALBERT LEA, MINNESOTA, A CORPORATION OF MINNESOTA.

DESIGN FOR A LABEL.

51,845.

Specification for Design.

Patented Mar. 5, 1918.

Application filed November 23, 1917. Serial No. 203,639. Term of patent 14 years.

To all whom it may concern:

Be it known that I, HENRY SOTH, a citizen of the United States, residing at Albert Lea, in the county of Freeborn and State of Minnesota, have invented a new, original, and ornamental Design for Labels, of which the following is a specification, reference being had to the accompanying drawing, forming part thereof.

The figure is a plan view of a label, showing my new design.

I claim:

The ornamental design for a label, as shown.

HENRY SOTH.

Witnesses:

D. D. DEVINE,
ANNA S. FRYDENLUND.
